[57] CLAIM

The ornamental design for the stunt riding toy, as shown and described.

DESCRIPTION

FIG. 1 is a perspective view of a stunt riding toy showing our new design;

FIG. 2 is a top plan view thereof;

FIG. 3 is a left side elevational view thereof, the right side elevational view being a mirror image;

FIG. 4 is a front elevational view thereof;

FIG. 5 is bottom plan view thereof; and,

FIG. 6 is a rear elevational view thereof.

The broken line showing of the flag and pole in FIGS. 1, 3, 4, and 6 is for illustrative purposes only and forms no part of the claimed design.
